UNITED STATES PATENT OFFICE.

LOUIS ERNEST FRANCOIS FERRETTE, OF PARIS, FRANCE.

INCANDESCENT SAFETY LAMP FOR MINES.

Original application filed February 17, 1922, Serial No. 537,295. Divided and this application filed November 21, 1923. Serial No. 676,155.

To all whom it may concern:

Be it known that I, LOUIS ERNEST FRANCOIS FERRETTE, engineer, citizen of the French Republic, residing at Paris, 41 Rue 5 Vital, Seine, France, have invented certain new and useful Improvements in Incandescent Safety Lamps for Mines, of which the following is a specification.

This invention has reference to miners' 10 safety lamps of the kind in which liquid illuminant is supplied through a vaporizer to a burner provided with a mantle for the production of an incandescent light, and in which means are also provided for controlling the supply of illuminant.

According to the present invention the means for controlling the supply of illuminant comprises a valve supported by flexible diaphragms (or a diaphragm) capable 20 of being adjusted in order to vary the position of the valve, so as to control the supply opening for the illuminant or to close said opening, as desired.

Preferably, there are two diaphragms, one 25 being disposed in the upper part of the lamp reservoir and freely supporting the valve which takes the form of a bell, and the other being disposed in the lower part of the reservoir, said diaphragms being interconnected by a rod. The lower diaphragm is engaged by an adjusting screw which when turned, causes both diaphragms to be moved in unison with a consequential movement of the ball towards or away from its seat.

35 When the lamp is inverted the ball moves by gravity to close the passage of the illuminant to the burner, thus obviating explosions.

In order that the invention may be clearly 40 understood, reference is made to the annexed drawing which illustrates, by way of example, a vertical sectional view of one form of the present invention as applied to a miner's safety lamp of the type described 45 in my Patent No. 1,496,261, granted June 3, 1924, of which the present case is a division.

Referring to the drawing:

As will be seen, the safety lamp comprises a main illuminant reservoir 1 within which 50 is disposed a smaller auxiliary reservoir 2 communicating with the said reservoir 1. The lamp also comprises a part 3 closing the reservoir 1; a brass nut or plug 4, screwed into the said part, closing an aper-

ture therein. A valve seat 7 is provided at 55 the under side of the plug 4 and is in communication with a tube 6 through which the vapors from the liquid illuminant contained in the reservoir 2 pass upwards to a burner 17 located at the upper end of the tube immediately below an incandescent mantle 5. A steel diaphragm 8 is disposed in the upper part of the main reservoir 1 and is provided, upon its upper face, with a cup 9 on which is supported a hardened copper ball 10 65 adapted, in a manner to be described hereafter, to close an aperture in the valve seat 7.

A diaphragm 12 is arranged in the lower part of the main reservoir 1 and is connected to the diaphragm 8 by means of a 70 rod 11 disposed between said diaphragms. An adjusting screw 14, screwed through a plate 13 attached to the bottom wall of the main reservoir, bears on the underside of the diaphragm 12.

75 As previously stated, the auxiliary reservoir 2 is in communication with the reservoir 1 and, therefore, also contains liquid illuminant. The vapors from said liquid illuminant pass upwards through a capillary 80 tube 15, preferably of copper, which is formed at its upper part with a coil or spiral, as will be seen from the drawing, and which serves as a suspension means for the mantle 5 and as a vaporizer for the liquid illuminant.

In operation, the vapors produced in the initially heated vaporizer 15 from the liquid illuminant enter a chamber 16 formed in the plug 4 and closed at its bottom by the diaphragm 8.

In order to allow the vaporized illuminant to pass upwards from the chamber 16 through the aperture in the valve seat 7 and through the tube 6 to the mantle 5, the adjusting screw 14 is loosened so that the ball 10 moves downwards away from the valve seat 7. When it is required to regulate the feed of illuminant to the mantle 5, it is only necessary to adjust the screw 100 14 so that the ball 10 is moved either nearer to or farther away from the valve seat 7, as required.

When the lamp is not lighted the ball 10 can be maintained in position against the valve seat 7 by means of pressure applied to the lower diaphragm 12 by the adjusting screw 14 and communicated by the rod 11

2
to the upper diaphragm 8 which forces the cup 9, and the ball 10 seated thereon, upwards.

If the lamp is inverted, it will be obvious
5 that the ball 10 will close the passage of the vaporized illuminant from the chamber 16 to the tube 6, cutting off the supply thereof to the mantle and thus obviating explosions.

Having now particularly described and
10 ascertained the nature of my said invention and in what manner the same is to be performed, I declare that what I claim is:—

11 1. A safety lamp, comprising a normally-open valve for controlling the supply of illuminant to the burner, adapted to move automatically into closed position when the lamp is overturned to shut off the supply; and a flexible diaphragm for supporting the valve adapted to be adjusted to vary 15 the normal position of said valve with relation to the supply opening for the illuminant.

12 2. A safety lamp, comprising a normally-open valve for controlling the supply of illuminant to the burner; a flexible diaphragm in the upper part of the lamp reservoir for freely supporting the valve; a flexible diaphragm in the lower part of said reservoir; a vertical rod connecting said 20 diaphragms; and an adjusting screw engaging the lower diaphragm for moving both diaphragms in unison with a consequent movement of the valve toward or from its seat.

13 3. A safety lamp, according to claim 2, in which the valve takes the form of a ball which automatically shuts off the supply of illuminant to the burner when the lamp is overturned.

14 4. A safety lamp, comprising a reservoir for liquid fuel; a burner; a tube leading thereto; a fuel feed system leading to the burner tube; a cup at the mouth of the

burner tube; a ball normally occupying said cup to leave the tube mouth open, but adapted to fall out of the cup into position to close said mouth and thereby arrest the feed when the lamp is overturned; and an adjusting device for moving said cup toward and from the tube mouth. 45
50

5. A safety lamp, comprising a reservoir for liquid fuel; a burner; a tube leading thereto; a fuel feed system leading to the burner tube; a cup at the mouth of the burner tube; a diaphragm whereon said cup is mounted; a ball normally occupying said cup to uncover the tube mouth, but adapted to fall out of the cup into position to close said mouth and thereby arrest the feed when the lamp is overturned; a vertical rod 55 having its upper end disposed immediately beneath said cup; and an adjusting device adjacent the lower end of said rod for moving the latter endwise to vary the position of the cup with relation to the tube mouth. 60
65

6. A safety lamp, comprising a reservoir for liquid fuel; a burner; a tube leading thereto; a fuel feed system leading to the burner tube; a cup at the mouth of the burner tube; a diaphragm whereon said cup is mounted; a ball normally occupying said cup to uncover the tube mouth, but adapted to fall out of the cup into position to close said mouth and thereby arrest the feed when the lamp is overturned; a diaphragm at the 70 bottom of the reservoir; a rod between the diaphragms having its upper end disposed immediately beneath said cup and its lower end supported on the lower diaphragm; and an adjusting screw beneath said lower diaphragm engaging the same in line with the said rod to raise or lower the latter and thereby vary the position of the cup with 75 relation to the tube mouth. 80
